204

UNITED STATES PATENT OFFICE.

PAUL ROSER, OF ESSLINGEN, GERMANY.

PROCESS FOR PRODUCING SODIUM PEROXID COMPOSITIONS FOR WASHING AND BLEACHING PURPOSES.

965,016.

Specification of Letters Patent. Patented July 19, 1910.

No Drawing.

Application filed February 8, 1909. Serial No. 476,672.

To all whom it may concern:

Be it known that I, PAUL ROSER, a citizen of the German Empire, residing at Esslingen, in the Kingdom of Würtemberg, Empire of Germany, have invented certain new and useful Improvements in Processes for Producing a Sodium Peroxid Composition for Washing and Bleaching Purposes; and I do hereby declare the following to be a full, clear, and exact description of the invention, such as will enable others skilled in the art to which it appertains to make and use the same.

This invention relates to an improved process for enabling sodium peroxid to be produced in a form better adapted for washing and bleaching purposes than has hitherto been the case.

Various disadvantages have been found in the use of sodium peroxid for washing and bleaching purposes. For instance, in the first place such a rapid violent and frequently explosive decomposition takes place on its contact with water that the nascent oxygen, which thus escapes much too rapidly, is only very incompletely utilized, and further the oxidizing action of the sodium peroxid when it comes in contact with the substances to be washed or the material to be bleached, is frequently so strong, that the articles in question are burned, and the handling of the sodium peroxid generally necessitates the greatest precaution. These properties of sodium peroxid therefore render its practical use for laundry and bleaching purposes extremely difficult.

Now this improved process has for its object to remove these unfavorable properties from sodium peroxid, and by the present invention this is done by the sodium peroxid being mixed with tetrachlorid of carbon until the mixture attains a pasty consistency, while a decomposition of the components either does not take place at all or only to a very inconsiderable extent. The pasty product thus obtained has in contrast to ordinary sodium peroxid, the advantage that, when placed in water, it immediately sinks, and under the protecting covering of the tetrachlorid of carbon only slowly and uniformly decomposes under the surface of the water. By this means a better utilization of the bleaching oxygen is possible than

was the case with the previous sudden decomposition. The tetrachlorid of carbon contained in the product also prevents any scorching or burning of organic substances, even when brought into direct contact with the preparation, and entirely deprives the sodium peroxid of its combustion producing tendencies, while on the other hand in consequence of its grease and resin dissolving properties, it considerably assists the cleaning power of the sodium peroxid in the washing or bleaching bath.

In all cases in which the caustic soda formed by the decomposition of the sodium peroxid might have a deleterious action, the free alkali may be rendered partially or wholly innocuous by the addition of suitable substances, such as sodium bicarbonate, boric acid and the like. These additions have also the advantage that the mass which is pasty without this addition, assumes a moist pulverulent condition by which the emptying of the vessels in which it is conveyed is considerably facilitated, so that it is no longer necessary to wash them out with water.

Other chlorin substitution products of the paraffin series which behave similarly to tetrachlorid of carbon may also be employed in the same manner.

Example 1: 55 parts of finely pulverized sodium peroxid are mixed in a mixing drum with 45 parts of tetrachlorid of carbon until a homogeneous paste is formed.

Example 2: 62 parts of finely pulverized sodium peroxid are treated in a mixing drum with 100 parts of tetrachlorid of carbon, 168 parts of sodium bicarbonate are added to the resultant thin paste, and the mass is mixed until it assumes a uniform moist pulverulent condition.

I declare that what I claim is:—

1. A process for producing a sodium peroxid composition suitable for washing and bleaching purposes, consisting in a non-combustible chlorin substitution product of the paraffin series, such for instance as tetrachlorid of carbon, being added to the sodium peroxid until a pasty constituency is obtained, substantially as described.

2. A process for producing a sodium peroxid composition for washing and bleaching purposes consisting in adding to a paste

of sodium peroxid and a noncombustible chlorin substitution product of the paraffin series a substance for neutralizing the free alkali of the soda.

5. 3. A process for producing a sodium peroxid composition consisting in adding to a paste of sodium peroxid and a noncombustible substitution product of the paraffin se-

ries sodium bicarbonate for neutralizing the free alkali. 10

In testimony whereof I affix my signature, in presence of two witnesses.

PAUL ROSER.
